ATTORNEYS.

UNITED STATES PATENT OFFICE

AUGUSTUS LUKE SCHARIO AND EDWARD PETER KIESWETTER, OF KITCHENER, ONTARIO, CANADA; SAID SCHARIO ASSIGNEE TO MAY EVELYN SCHARIO, OF KITCHENER, ONTARIO, CANADA

DISPLAY RACK

Application filed October 13, 1932. Serial No. 637,583.

This invention relates to racks and particularly to racks for displaying magazines, newspapers, cards and the like.

The object of the invention is to provide a simple and economical construction in which publications may be displayed to best advantage in substantially erect position. A further object is to provide a construction which may be locked to prevent unauthorized removal of the publications, which will retain the publications in good order without folding or drooping of the loose edges thereof and which is of light weight so that it may be conveniently moved from one place to another without removing the publications. The rack containing the magazines or the like may be placed in front of a news-stand or shop during business hours and stored inside at closing time.

20 The invention consists in the novel features of construction and in the arrangement and combination of parts hereinafter described with reference to the accompanying drawing and more particularly defined in the appended claims.

In the drawing,

Figure 1 is a vertical elevation of the rack; Figure 2 is a side elevation thereof; and

30 Figure 3 is a detail section showing the locking arrangement.

In the drawing, 1 represents a backing plate which is normally about one-third of the width of the rack, and to which spring clips 2 are riveted at spaced points, the distance between the clips being determined by the length of the articles to be displayed. These clips preferably have a rounded top 3 and are of sufficient width to support the publications. Cross rods 4, preferably of wire in the form of a substantially rectangular loop, are located at spaced points along the backing plate. These rods provide horizontal supports for the magazines or the like. In the form shown the ends of these rods project through side flanges 5 on the backing plate, as illustrated in Figure 2, and are soldered or otherwise secured along the centre of the back of the backing plate, one end of each rod being bent at right angles to its length, as at 6, to give a greater bearing sur-

face. The clips 2 and the cross rods 4 hold the magazines or the like in erect neat position.

Locking means are provided to insure against unauthorized removal of the magazines as well as interference with their orderly arrangement. In the illustration, shown in detail in Figure 3, this locking means comprises a rod 7 the ends of which pass through supporting lugs 8 mounted adjacent the ends of the backing plate 1. The lugs 8 are provided with a screw-threaded recess 9 adapted to receive a set screw 10 which locks the rod 7 in place in the lugs. The screw has a hexagonal head or other suitable means adapted to receive a key or the like to open or close the lock.

At least one of the cross rods 4 is loosely connected to the locking rod 7, as by a loop or eye in the rod 4, as illustrated at 11 in Figures 1 and 2, to support the locking rod about the middle portion of its length. The rod 7 is positioned within the rectangular loops of the cross-rods 4 as shown.

In filling the rack with magazines or the like the set screws 10 are partially withdrawn to allow the locking rod 7 to be lowered while the upper section of the rack is filled. The rod is then pushed upwardly in the eye 11 and upper lug 8 to permit of filling the lower section of the rack when the rod is lowered into position in the bottom lug 8, and locked by inserting the set screws. Obviously the locking rod 7 may be entirely removed while filling the rack.

It will be apparent that with a rack of this character the magazines are securely located in an attractive and orderly arrangement for display purposes. By virtue of the arrangement of the closed locking bar 7 in combination with the rectangularly looped cross-rods 4 the magazines cannot be withdrawn.

The construction is preferably entirely of metal. The cross-rods and clips may be of steel and the locking device of brass, although any suitable materials may be used. The rack is conveniently made in different sizes to best accommodate different sized articles to be displayed.

We claim:

1. A rack of the kind described, comprising in combination a backing plate, spring clips secured thereto in spaced relation, rec-
5 tangularly looped rods secured to said back-
ing plate in spaced relation to said clips, said
clips and looped rods providing vertical and
lateral supports for magazines and the like
and locking means to prevent removal of said
10 magazines from the rack.
2. A display rack for magazines and the like, comprising a backing plate, spring clips secured thereto to provide vertical supports, looped rods secured to said plate in spaced
15 relation to said clips to provide lateral sup-
ports, a rod disposed lengthwise of said plate
and movably mounted in a support at each

end thereof and means for locking said rod in
said supports.

3. A display rack for magazines and the like comprising in combination a backing plate, vertical supports on said plate for
70 said magazines, spaced apart looped mem-
bers positioned on the backing plate for sup-
porting said magazines laterally, lugs adjac-
ent the ends of said plate, a rod movably
75 mounted in said lugs and means for locking
said rod in said lugs.

4. A display rack as defined in claim 3,
wherein said rod is movably connected with
at least one of said looped members.

AUGUSTUS LUKE SCHARIO.
EDWARD PETER KIESWETTER.
